UNITED STATES PATENT OFFICE

EDWARD R. McCRAFFERTY, OF PITTSBURGH, PENNSYLVANIA

AUTOMATIC OIL SEPARATOR

Application filed October 13, 1931. Serial No. 568,644.

The present invention relates to an automatic oil separator for low pressure refrigerating machines and has for its prime object to provide a device of this nature which will separate the oil from the gas so as to save the oil from being wasted and doing harm in the cooling unit of the refrigerating machine.

Another very important object of the invention resides in the provision of an oil separator of this nature which is simple in its construction, inexpensive to manufacture, thoroughly efficient and reliable in use and operation, compact in its arrangement of parts, thoroughly efficient and reliable in operation and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a vertical longitudinal section taken through the device.

Figures 2, 3, 4 and 5 are transverse sections taken respectively on the lines 2—2, 3—3, 4—4 and 5—5 of Figure 1, and

Figure 6 is a sectional view through the float.

Referring to the drawings in detail it will be seen that the numeral 3 denotes an elongated cylinder open at both ends and having both ends externally threaded. On the upper end of the cylinder 3 there is mounted top head 1 having formed therein the central inlet opening 20 and the off center outlet opening 21. A collar 2 depends from the edge of the top head 1 and is threadedly engaged about the top end of the cylinder 3. Numeral 6 denotes a gas inlet tube extending from the bottom end of the opening 2 and terminating above a partition plate 7 formed with perforations 23 adjacent the edge thereof. This partition plate 7 is located immediately above the center of the cylinder.

Numerals 4 denote frusto-conical baffles having a close fit against the inside of the cylinder 3 while numerals 4' denote similar

baffles fixed to the tube 6 and arranged alternately with respect to the baffles 4. The baffles 4 are supported by rods 5 extending from the tube 6 while baffles 4' are braced by rods 5' extending from the tube 6.

Numeral 8 denotes a hollow float with a depending needle valve 9 extending through a guide 10. Numeral 11 denotes a needle valve seat, a portion of which extends into oil outlet openings 25 of bottom head 13. This bottom head 13 is provided with a collar 12 threaded about the lower end of the cylinder 3.

Numeral 26 denotes a clean out plug threaded in an opening in the bottom head 13. The working and advantages of the oil separator are as follows:

The oil laden gas vapor is forced by the compressor into the separator through the gas inlet tube. The oil is removed from the gas vapor by the baffle and drops down into the bottom of the separator. The gas now free from the oil continues to flow upward and out through the outlet connection to the condenser. When the oil has reached a certain level in the bottom of the separator it will raise the float and needle valve and the oil will return to the crank case of the compressor.

The advantages of this separator are— first: All the oil which will have to be used will be in the crank case of the compressor. As it is now, the cooling unit has a charge of oil and the sump has a charge of oil and also the crank case. Second: there will be no oil pumped over into the condenser which has a tendency to insulate the inlet of the condenser tube and lower the capacity of the condenser. Third: no oil will find its way up into the cooling unit, to cause oil logging and reducing the capacity of the cooling unit. Fourth: the crank case of the compressor will always have its proper supply of oil which will keep the working parts lubricated and thereby prolong the life of the compressor. There is also an obvious saving of oil and the capacity of the separator will be increased.

It is thought that the construction, operation, utility and advantages of this inven-

tion will now be quite apparent to those skilled in this art without a more detailed description thereof.

The present embodiment of this invention 5 has been described in considerable detail merely for the purposes of exemplification since in actual practice it attains the features of advantage enumerated as desirable in the statement of the invention and the above de- 10 scription.

It will be apparent that changes in the details of construction, and in the combination and arrangement of parts may be resorted to without departing from the spirit 15 or scope of the invention as hereinafter claimed or sacrificing any of its advantages.

Having thus described my invention, what I claim as new is:

1. A separator of the class described in- 20 cluding a cylinder, a top head for the cylin- der, a bottom head for the cylinder, said top head being provided with an inlet opening and an outlet opening, a tube extending from the top head communicating with the inlet 25 opening down into the cylinder, baffles ex- tending inwardly from the inside of the cyl- inder about the tube, and baffles extending outwardly from the tube alternately arranged with respect to the first baffles, a partition 30 across the cylinder below the tube and hav- ing perforations, said bottom head having an outlet opening, and float valve control means therefor.

2. A separator of the class described in- 35 cluding a cylinder, a top head for the cylin- der, a bottom head for the cylinder, said top head being provided with an inlet opening and an outlet opening, a tube extending from the top head communicating with the inlet 40 opening down into the cylinder, baffles ex- tending inwardly from the inside of the cyl- inder about the tube, and baffles extending outwardly from the tube alternately ar- ranged with respect to the first baffles, a par- 45 tition across the cylinder below the tube and having perforations, said bottom head having an outlet opening, a needle valve seat in said last mentioned opening, a guide about the seat and rising therefrom, a needle valve 50 extending through the guide to engage with the seat, and a float fixed to the upper end of the needle valve.

In testimony whereof I affix my signature.
EDWARD R. McCLAFFERTY.
